UNITED STATES PATENT OFFICE.

HERMANN CLARE, OF BERNE, SWITZERLAND.

ENVELOPE.

1,418,620.

Specification of Letters Patent. Patented June 6, 1922.

Application filed December 18, 1918. Serial No. 267,389.

(GRANTED UNDER THE PROVISIONS OF THE ACT OF MARCH 3, 1921, 41 STAT. L., 1313.)

To all whom it may concern:

Be it known that I, HERMANN CLARE, a citizen of the Swiss Confederation, and residing at Berne, Switzerland, have invented 5 a certain new and useful Improvement in Envelopes (for which I have filed applications in Switzerland Dec. 15, 1916; in Germany April 27, 1917; in France Dec. 14, 1917, Patent No. 487,991, delivered May 21, 10 1918, and in Great Britain Dec. 15, 1917, Patent No. 112,027, complete accepted Dec. 16, 1918), of which the following is a specification.

The present invention relates to certain 15 new and useful improvements in that class of envelopes in which a cut-out or transparent "window" is presented, for showing the address written at the head of the enclosed letter and making it serve as address for the envelope also. For the same purpose and also 20 for the purpose of doing away with a separate letter sheet, that is making the envelope serve simultaneously also as letter sheet, it has been proposed to use sheets which 25 when written upon can be folded up to form their own envelope, in such manner that then the address written at the head of the sheet shows either on a folded-over flap thereof or through an aperture bounded by several 30 such flaps integrally extending from the sheet. For business correspondence envelopes are used on which the sender's name, address and other information is printed at relatively high cost, which in the second 35 named instance is reduced somewhat, it is true, but which has the disadvantage that, in case such a letter head from some cause becomes unusable, the printed part and the folding flaps also are wasted.

40 The object of the present invention is to combine the advantages of these known arrangements without at the same time taking over their objectionable features, and for the purposes of my invention I provide the envelope portions forming the address space 45 or window with gum and paste them onto the underlying letter or other contents of the envelope, and I also provide tearing lines along which these pasted-on flaps may be 50 severed from the rest of the envelope upon the latter being opened, the flaps then remaining affixed to the letter sheet and henceforth forming a permanent part thereof. One of these window forming portions may

be printed upon in suitable manner, for instance with the "card" of the sender. 55

A great advantage over other makes of envelopes is that the part of the envelope, valuable for future reference, containing the postage stamp with the date stamp, registry 60 indications, and other data, remains permanently affixed to the letter sheet after the envelope proper has been opened and destroyed.

In order to make my invention more readily understood, I will now describe it in detail with reference to the accompanying drawing, in which Fig. 1 represents a front elevation of a preferred form of my new envelope, of which Fig. 2 is a vertical section; Fig. 3 shows a front view of a modification; Fig. 4 is a section on line IV-IV of Fig. 3, and Fig. 5 is a front view of still another modification, of which Fig. 6 shows a section on line VI-VI. 75

Referring first to Figs. 1 and 2, the envelope is preferably of rectangular shape and its front member 1 is somewhat shorter than the rear member 2, so that the latter extends downwardly beyond the former. Both 80 members are respectively provided at their lower longitudinal edge with a strip 3 and 4, and a weakened or perforated line 6 is interposed between strip 4 and member 2. The latter is provided at their lower sides 85 extending beyond the front member 1 with laterally extending flaps 7 and 8, which owing to an interposed weakening line 9 and 10 respectively can readily be detached from the envelope body. The strips 3 and 4 and 90 the flaps 7 and 8 are gummed, the strip 3 on the inside and the other parts on the outside, which latter parts in the closed envelope are bent back upon themselves. The front member 1 is provided with marginal 95 weakening lines or series of perforations 11, so that these marginal portions can readily be torn off.

In use, the letter sheet or other enclosure 100 is inserted into the envelope and the latter is closed by first sealing the gummed strip 3 to the enclosure, then folding over the side flaps 7 and 8 along the lines 12 and sealing them down, and finally folding over the strip 4 on its line 6 and sealing it also to 105 the contents. The envelope is then securely closed and simultaneously affixed to the contents, and an oblong window 13, with the

parts 3, 4, 7 and 8 serving as frame, is presented, into which the address can be written, unless it has not already been inserted when writing the letter. The address thus, 5 in any case, need be written only once. The postage stamp can preferably be affixed in the space designated by 14, but it may, obviously, also be attached at any other point, for instance in the upper right-hand corner. 10 It is thus permanently secured to the letter and serves to preserve for future reference the indication of the mailing place and date. In the case of a registered letter, for instance, it cannot be claimed that no letter 15 had been enclosed in the envelope.

For opening such a sealed envelope it is cut open or torn along the weakened lines 6, 9, 10 and 11 and also along the upper longitudinal bending line where front and back 20 meet. The front portion 1 may bear the sender's name, address, trade-mark, and like matter and it remains stuck to the letter sheet.

In the modification according to Figs. 3 25 and 4, the size of the envelope relative to the letter sheet 15, indicated by a dash-dotted line, is to be such that when the sheet is inserted between the front and rear envelope members, the envelope will project on 30 three sides. A rearwardly gummed member 16 is sealed to the letter and to the respectively projecting marginal portions of the members 1', and 2', which closes the envelope. The member 16 is provided with a 35 cut-out 13' for displaying the address written on the enclosure. Along the marginal edges the envelope parts may be provided with weakened lines or series of perforations, not shown in the drawing, along which 40 the envelope may be opened. If the sealing strip 16 is of transparent material the cut-out window 13', obviously, may be dispensed with.

In the modification illustrated in Figs. 5 45 and 6, the rear portion 2" of the envelope is shorter than the front portion 1" by the

width of a marginal strip 17, and this projecting strip which is gummed is bent upon itself and pasted to the rear face of the back portion 2", as indicated by dotted lines in 50 Fig. 6, after the rearwardly gummed front member 1", which is provided with a cut-out or transparent window 13", has been moistened and affixed to the letter or other matter inside the envelope and to the marginally projecting portions of the back member 2", the gummed marginal strips 18 and 19 of the front member being sealed to corresponding strips of the back member. The envelope is opened by tearing off these 60 side strips and by severing the front from the back member along their longitudinal meeting edge, which tearing lines are indicated by the lines 20, 21, 22 and 23.

It is to be understood that the envelope 65 may also be of other shape than the oblong form shown, and the space for receiving the address may, obviously, also be positioned in some other portion of the front member, instead of in the lower portion as shown by 70 way of example.

What I claim is:—

An envelope composed of a sheet folded to form a front and a back portion, the latter being of greater length than the former 75 and the front portion having adhesive on the under side to attach it to the contents of the envelope, a foldable adhesive flap on the end of the back portion and foldable adhesive flaps on the lateral edges of that part 80 of the back portion which extends beyond the edge of the front portion, weakening lines being provided along the sides and bottom of the envelope to facilitate its opening.

In testimony whereof, I affix my signature in the presence of two witnesses.

HERMANN CLARE.
